UNITED STATES PATENT OFFICE

NICHOLAS W. KYLE, OF COLFAX, ILLINOIS

HOISTING DEVICE

Application filed September 10, 1928. Serial No. 305,047.

This invention relates to improvements in a hoisting device which is well adapted for use on a dump body of an automobile truck, and will be described as such in this specification. It may, however, be very well adapted in numerous other ways where a hoist of this description is used.

The object of the invention is to provide a lifting device leg means of two lifting 10 jacks each having four toggle levers which unfold in hoisting the truck body, and fold again around the operating shaft when the truck body is lowered to its natural position and thus lock the body firmly in this position.

A further object is to have a device of the kind described that may be located underneath the front end of the truck body where it will have direct, quick, easy, and well 20 balanced lift, and will be protected from mud, sand, and ice.

A still further object is to provide for either hand operation or power operation from the truck engine, and a ratchet device 25 to hold the truck body at any desired angle.

With these and other objects in view, as will appear as the description proceeds, the invention consists in the novel construction and arrangement of parts as hereinafter more 30 specifically set forth, claimed and shown in the accompanying drawings forming a part of this present application and in which:

Fig. 1 is a perspective view of my invention as applied to a dump truck body.

Fig. 2 is a plan view of one of the folding 35 hoist jacks.

Fig. 3 is a side elevation of the same.

Fig. 4 is a cross-section on line A—A of 40 Fig. 3.

Fig. 5 is a cross-section on line B—B of Fig. 3.

Fig. 6 shows the hoist jack fully extended.

Fig. 7 shows the hoist jack partially folded.

Fig. 8 shows the hoist jack completely 45 folded with the truck body in natural position.

Referring more in detail to the drawings in which similar reference characters designate corresponding parts throughout the 50 several views it will be seen that the inven-

tion consists of a pair of folding hoist jacks comprising a series of toggle levers designated hereafter as "C", "D", "E", and "F". As these jacks are identical in construction it will suffice to describe one only.

The toggle lever "C" is secured to the under structure of the truck body by a pin through the orifice 10 and is pivotally hinged to the toggle lever "D" by an outwardly extending boss 11 on the lower end. "D" is made in two sections and clamped together by the bolts 12, one end is provided with receptacles for the boss 11, and the other end has an inwardly projecting boss 13 onto which connection is made to the toggle lever "E". This toggle lever "E" is made in two parts and clamped together by the bolts 14 and is likewise provided with receptacles for the boss 13 and has an outwardly extending boss 15. Toggle lever "F" is also made in two parts and clamped together by the bolt 16. Receptacles for the boss 15 are provided at one end and orifices 17 provided at the lower end for a pin 18 upon which the hoist is pivoted to the operating mechanism. Said pin 18 and a similar pin 19 are secured at one end to the gear wheel 20 and at the other end to a member 21 mounted on the main shaft. In each of the joints of the toggle levers is a U shaped recess 22 for the pins 18 and 19 upon which the toggle levers fold. When the pins 18 and 19 are partially in place they make contact with the members 23, which extend through the joint from the locking arm 24, pushing said member 23 outwards thereby releasing the locking device and permitting the toggle levers to fold. This locking device is made by protrusions 25 on the locking arms 24, and the recesses 26 in the joints. The locking arms are held in place by springs 27 on the bolts 28. The locking device on toggle lever "F" is of slightly different construction but is numbered similarly to simplify the explanation.

The jacks, as previously mentioned are pivoted to the gear wheels 20 which are mounted on a shaft 30 having its bearings 31 on the chassis frame 32. The drive as shown is for hand operation. The crank 33 being of the folding type is keyed to a shaft 34

mounted in the frame 35 and the bearing 36 on the chassis frame 32. At its inner end is keyed a small gear wheel 37 which engages a larger gear wheel 38 keyed to a counter-shaft 5 39. Said counter shaft is mounted in the bearings 40 on the chassis frame 32. Keyed to this shaft 39 are two small gears 41 designed to engage the gears 20.

The ratchet locking device is secured to 10 the frame 35, and consists of a double pawl 42 pivoted to the frame 35 and a toothed ratchet wheel 43 keyed to the shaft 34. This device will operate in either direction by moving the pawl 42 to engage the ratchet wheel 15 43 on one side or the other.

It is believed that the construction and advantages of the structure shown may be apparent from the foregoing paragraphs taken 20 in connection with the accompanying drawings without further detailed description.

While the preferred embodiment of the invention has been disclosed it is understood that minor changes in the details of construction, combination and arrangement of 25 co-operating elements may be resorted to within the scope of what is claimed without departing from the spirit of the invention.

What I claim:

30 1. In a hoisting device of the character described the combination of a support, a tilt-able member, a rotor mounted on said support and including a pair of diametrically opposed pins spaced equidistantly from the axis thereof, a series of toggle levers hinged 35 together end to end, the terminal levers being respectively pivoted at their outer ends to one of said rotor pins and the tilttable member, said hinged points between the levers having slots, the distance between the slots of 40 each joint being equal to the distance between the pins on said rotor, whereby the slots receive and engage the pins on the rotor when the levers are wound upon the rotor, locking arms for holding said toggle levers in ex- 45 tended relation and means associated with said locking arms adapted to be engaged by the pins on said rotor to release said locking arms, so that the toggle levers may be wound upon the rotor.

50 2. In a hoisting device of the character described the combination of a support, a tilt-able member, a rotor mounted on said support, and including a pair of diametrically opposed pins spaced equidistantly from the 55 axis thereof, a series of toggle levers hinged together end to end, the terminal levers being respectively pivoted at their outer ends to one of said rotor pins and the tilttable member, said hinged points between the levers having slots, the distance between the slots of 60 each joint being equal to the distance between the pins on said rotor, whereby the slots receive and engage the pins on the rotor when the levers are wound upon the rotor, locking arms for holding said toggle levers 65

in extended relation and pins extending from said arms into said slots, adapted to be engaged by the pins on said rotor when the toggle levers are wound thereon, whereby the locking arms are automatically released. 70

3. In a hoisting device of the character described the combination of a support, a tilttable member, a rotor mounted on said support and including a pair of diametrically opposed pins spaced equidistantly from the axis thereof, a series of toggle levers hinged together end to end, the terminal levers being respectively pivoted at their outer ends to one of said rotor pins and the tilttable member, said hinged points between the levers having slots, the distance between the slots of each joint being equal to the distance between the pins on said rotor, whereby the slots receive and engage the pins on the rotor when the levers are wound upon the rotor, spring actuated locking arms for holding said toggle levers in extended relation and members extending from said arms into said slots adapted to be engaged by the pins on said rotor whereby the arms are automatically released to permit winding of the toggle levers on the rotor. 80

In testimony whereof I affix my signature.

NICHOLAS W. KYLE.
